M. L. DAVIS

SANDAL

Filed June 28, 1926

FIG. 1

FIG. 2

FIG. 3

Inventor;
Miriam L. Davis,
Attorney,
Horace Barnes

UNITED STATES PATENT OFFICE.

MIRIAM L. DAVIS, OF PORTLAND, OREGON, ASSIGNOR OF NINE-TWENTIETHS TO J. H. BERRY, OF PORTLAND, OREGON.

SANDAL.

Application filed June 28, 1926. Serial No. 118,947.

This invention relates to improvements in sandals, and has for its principal object the provision of a sandal or light slipper of extremely simple and economical construction and which may be made from a single sheet of material.

A further object of the invention is the provision of a sandal having side portions retained together to receive the foot by an elastic cord, whereby the sandal is resiliently supported on the foot.

A still further object of the invention is the provision of a sandal employing an elastic band which may be detachably connected to the toe of the sandal and thence engaged with the side portions of the sandal, whereby the sandal is resiliently retained at its toe portion in close engagement with the toes of the wearer and through which the sandal is adaptable for wear on feet of many sizes, so that a serviceable and comfortable sandal may be provided at a minimum of parts and expense.

Other objects and advantages of my invention, and objects relating to details of construction and arrangement of parts will be readily apparent in the course of the detailed description to follow.

The accompanying drawings illustrate by way of example a preferred form of the invention, in which:

Figure 1 is a view in side elevation of a sandal embodying my invention shown mounted upon a human foot.

Fig. 2 is a plan view of my improved sandal arranged in working condition.

Fig. 3 is a plan view of my improved sandal before the same is folded.

Referring to said views, the reference numeral 1 indicates the body or sole portion of my improved sandal which may be blanked out from a sheet of suitable material, such as cardboard, leather, or various imitations of leather. Said body is provided with integral flaps 2 extending symmetrically upon each side of the forward or tread portion of the sole, which flaps are creased at their junction 3 with the sole and are again creased at 4 in outward, spaced relation from the crease 3 and at slight converging direction to the crease 3.

Adjacent the outer extremities of each of the flaps a tongue 5 is formed in the flap material directed toward the longitudinal axis of the body. Adjacent the toe portion

of the sandal-sole a tongue 6 is formed in the sole material directed toward the rear of the sandal. A supplementary hole 7 is formed in the forward extremity of the sandal and in the longitudinal axis thereof.

The sandals are made of identical configuration, there being no rights and lefts, and are formed and prepared for use by folding the flaps 2 along the creases 3 and 4, so that the flap ends will meet or overlap in the central line of the sandal.

A rubber band 8 may then be engaged about each of the tongues 5 providing a portion 9 extending across and resiliently uniting the two flaps. The band is then extended longitudinally in parallel portions 10 over and under the front end of the sandal toe and engaged over the tongue 6.

The sandal is thus prepared for wearing. The foot may be thrust therein, which will spread the two flaps apart to some extent and cause the portion 9 of the elastic band to stretch somewhat, giving an elastic support to the sandal upon the instep. The toes of the wearer will be thrust forwardly and engage the parallel portions 10 of the elastic band, but with such slight pressure as to be unnoticeable, although sufficient to give efficient support and a snug, secure feeling of the sandal upon the foot.

In wearing the sandal, it will be found that the elastic pressure of the flaps over the instep of the wearer will support the rear portion of the sandal closely to the heel of the wearer when the foot is lifted from the floor; also, that the resilient upward tension of the band 8 on the toe of the sandal will slightly bend said toe portion upwardly, as indicated at 11 in Fig. 1, so that the sandal toe will not catch in carpets or rugs as the wearer walks, but will be retained in close engagement with the toes.

Where it is desired to have the band 8 fixed more permanently to the sandal than the illustrated connection thereof, about the tongue 6, a bight of the band may be threaded through the hole 7 from the bottom in a loop, not shown, and then the band brought through said loop and extended rearwardly about the tongues 5. In this manner the bands may be more permanently fixed to the sandal, but otherwise the arrangement is similar.

The present invention is particularly advantageous and desirable for use as a tem-

porary slipper or sandal in hospitals or hotels where patients or guests are in temporary residence and may be unprovided with slippers. Slippers made in accordance with 5 my invention may be made of a wide variety of materials, some of which are so inexpensive that a pair may be made and supplied to the guests at such a low cost that they can be used once or a few times and 10 then thrown away without extravagance.

In this manner, hospitals, hotels, and the like may supply their guest with this added convenience at small cost and with perfect regard for sanitary requirements.

15 From the foregoing description taken in connection with the accompanying drawings the advantages of the construction and application of my improved sandals will be readily apparent, but, while I have described 20 the principle of operation of the invention together with the devices which I now consider the best embodiment thereof, it will be understood that the structures shown are merely illustrative, and that such modifications and minor changes may be made therein as will lie within the scope of the following claims.

Having described my invention, what I claim, is:

1. A sandal of the class described, consisting in a body-sole portion, formed of

sheet material having a pair of integral flaps extending upon opposite sides of said sole-portion, said flaps provided with inwardly directed tongues, and an endless elastic cord 35 engaged about said tongues and thence extended forwardly for connection with the toe of the sole-portion.

2. A sandal comprising a single sheet of material including a sole-portion and integral laterally extending flaps extending from each side, and an endless elastic cord fastened at the forward end of said sole-portion and detachably connected to said flaps.

3. A sandal comprising an integral sheet 45 of material including a sole-portion and laterally extending flaps adapted to lie over the wearer's instep, said flaps being each formed with a tongue, and a cord secured to the forward portion of said sole-portion and 50 thence detachably engaged with said tongues.

4. A sandal comprising an integral sheet of material including a sole-portion and laterally extending flaps adapted to lie over the wearer's instep, said flaps being each formed with a tongue, and an elastic cord secured to the forward portion of said sole-portion and thence detachably engaged with 55 said tongues.

MIRIAM L. DAVIS.
